Primary Examiner — Paula Greene(74) *Attorney, Agent, or Firm* — NSIP Law(57) **CLAIM**

We claim the ornamental design for a cap for headset, as shown and described.

DESCRIPTION

FIG. 1 is a front perspective view of a cap for headset showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross sectional view taken along the line 8-8 of FIG. 6;

FIG. 9 is an another perspective view thereof, as shown a headset environment; and,

FIG. 10 is an enlarged exploded view of a portion of the cap for headset of FIG. 9.

The broken lines in the figures show portions of the cap for headset which form no part of the claimed design.

The dot-dash broken lines encircling enlargement portions of the design forms no part of the claimed design.
